[57] CLAIM

The ornamental design for a writing instrument holder, as shown and described.

DESCRIPTION

FIG. 1 is a top plan view of a writing instrument holder showing my new design, the bottom plan view being a mirror image thereof;

FIG. 2 is a side elevational view, the opposite side being a mirror image thereof;

FIG. 3 is an end elevational view taken from the left end of FIG. 1;

FIG. 4 is an end elevational view taken from the right end of FIG. 1;

FIG. 5 is a cross-sectional view taken in the direction of arrows 5—5 in FIG. 1;

FIG. 6 is a cross-sectional view taken in the direction of arrows 6—6 in FIG. 1;

FIG. 7 is a top perspective view; and

FIG. 8 is a side elevational view with the support portion angled to an alternate position.

The pen depicted by means of broken lines in FIG. 8 is for illustrative purposes only and forms no part of the claimed design.
